[57] CLAIM

The ornamental design for a pocket note-book, as shown and described.

DESCRIPTION

FIG. 1 is a front perspective view of a pocket notebook showing my new design;

FIG. 2 is an enlarged scale top plan view thereof;

FIG. 3 is a front elevation view (rear elevation view in symmetry) thereof;

FIG. 4 is a right-side elevation view thereof;

FIG. 5 is a bottom plan view thereof;

FIG. 6 is a left-side elevation view thereof; and,

FIG. 7 is a reduced scale front elevational view thereof, the broken lines shown are for illustrative purposes only and form no part of the claimed design.
